(57) **CLAIM**

The ornamental design for a bottled beverage preservation cap, as shown and described.

DESCRIPTION

FIG. 1 is a front top perspective view of the bottled beverage preservation cap of the present invention;

FIG. 2 is a back bottom perspective view thereof;

FIG. 3 is a top view thereof;

FIG. 4 is a bottom view thereof;

FIG. 5 is a front view thereof;

FIG. 6 is a back view thereof;

FIG. 7 is a left side view thereof; and,

FIG. 8 is a right side view thereof.

The broken lines shown in the drawings depict portions of the "bottled beverage preservation cap" that form no part of the claimed design.

1 Claim, 5 Drawing Sheets
